(57) **CLAIM**

The ornamental design for a trunk organizer, as shown and described.

DESCRIPTION

FIG. 1 is a top plan view of a trunk organizer, showing my new design;

FIG. 2 is a bottom plan view thereof;

FIG. 3 is a right side elevation view thereof;

FIG. 4 is a left side elevation view thereof;

FIG. 5 is a front elevation view thereof;

FIG. 6 is a rear elevation view thereof;

FIG. 7 is a front perspective view thereof; and,

FIG. 8 is a rear perspective view thereof.

The broken lines in the Figures show portions of the trunk organizer which form no part of the claimed design.
